(57) **ABSTRACT**

A head driving mechanism includes a first cam follower an end portion of which is attached to a first holding unit and the other end portion of which includes a first sliding-contact surface disposed in sliding contact with a cam, and a second cam follower an end portion of which is attached to the second holding unit and the other end portion of which includes a second sliding-contact surface disposed in sliding contact with the cam. The first cam follower and the second cam follower are each displaced by rotation of the cam so as to move the first printing head and the second printing head, while the first sliding-contact surface and the second sliding-contact surface are in sliding contact with an outer circumferential surface of the cam.

HEAD MOVING MECHANISM AND PRINTING APPARATUS

CROSS-REFERENCE TO RELATED APPLICATIONS

The entire disclosure of Japanese Patent Application No. 2012-100983, filed Apr. 26, 2012 is expressly incorporated by reference herein.

BACKGROUND

1. Technical Field

The present invention relates to a head driving mechanism that drives a plurality of printing heads, and a printing apparatus including the head driving mechanism.

2. Related Art

JP-A-2011-67964 (in particular, see FIG. 1) discloses a printing apparatus that dispenses a liquid such as ink or recording fluid from a plurality of printing heads onto a recording medium such as a film, to thereby record color images. In this apparatus, the recording medium is wound, with a predetermined tension applied thereto, around a circular column-shaped platen drum the recording medium, and supported on the curved surface of the platen drum. The plurality of printing heads are provided around the circumferential surface of the platen drum.

To record high-quality images, it is essential that a paper gap, in other words a distance between a nozzle tip (outlet of the ink) of the printing head and the recording medium is maintained at a proper value, and hence the printing heads have to be moved according to the thickness of the recording medium, to thereby locate the printing heads at a proper distance from the platen drum with high accuracy. However, no specific reference is made in JP-A-2011-67964 about such a positioning method.

According to JP-A-2011-67964, in addition, the printing heads are radially arranged with respect to the rotation axis of the platen drum, so that, with respect to the landing position of the ink, the printing heads of the respective colors are oriented perpendicular to the curved surface of the platen drum. Accordingly, on the assumption that one of the printing heads is set to move in a first direction, another printing head has to be moved in a second direction which is inclined with respect to the first direction, and thus the printing heads have to be moved in different directions. Therefore, many of the printing apparatuses of such a type include head driving mechanisms provided for the respective printing heads, for moving the printing heads in a direction perpendicular to the curved surface of the platen drum.

However, providing the same number of head driving mechanisms as that of the printing heads not only constitutes a major factor that increases the size and cost of the printing apparatus, but also makes it difficult to locate the printing heads at the correct position with high accuracy, because of individual variation among the head driving mechanisms.

SUMMARY

An advantage of some aspects of the present invention is provision of a small-sized head driving mechanism that can be manufactured at a lower cost, the head driving unit being capable of moving a first printing head in a first direction and a second printing head in a second direction different from the first direction, and a printing apparatus that includes such a head driving mechanism.

2

In an aspect, the present invention provides a head driving mechanism including a first holding unit that holds a first printing head so as to move in a first direction, a second holding unit that holds a second printing head so as to move in a second direction inclined with respect to a first direction, a rotary actuator that generates rotative driving force for driving the first printing head and the second printing head, a cam shaft to be driven to rotate by the rotative driving force from the rotary actuator, a cam attached to the cam shaft, a first cam follower an end portion of which is attached to the first holding unit and the other end portion of which includes a first sliding-contact surface disposed in sliding contact with the cam, and a second cam follower an end portion of which is attached to the second holding unit and the other end portion of which includes a second sliding-contact surface disposed in sliding contact with the cam. The first cam follower and the second cam follower are each displaced by rotation of the cam so as to move the first printing head and the second printing head, while the first sliding-contact surface and the second sliding-contact surface are in sliding contact with an outer circumferential surface of the cam.

In another aspect, the present invention provides a printing apparatus including a rotatable roller, a first printing head that dispenses a first liquid in a first direction onto a recording medium wound around a surface of the roller, a second printing head that dispenses a second liquid in a second direction inclined with respect to the first direction onto the recording medium wound around the surface of the roller, and a head driving mechanism that drives the first printing head and the second printing head. The head driving mechanism includes a first holding unit that holds the first printing head so as to move in the first direction, a second holding unit that holds the second printing head so as to move in the second direction, a rotary actuator that generates rotative driving force for driving the first printing head and the second printing head, a cam shaft driven to rotate by the rotative driving force from the rotary actuator, a cam attached to the cam shaft, a first cam follower an end portion of which is attached to the first holding unit and the other end portion of which includes a first sliding-contact surface disposed in sliding contact with the cam, and a second cam follower an end portion of which is attached to the second holding unit and the other end portion of which includes a second sliding-contact surface disposed in sliding contact with the cam. The first cam follower and the second cam follower are each displaced by rotation of the cam so as to move the first printing head and the second printing head, while the first sliding-contact surface and the second sliding-contact surface are located adjacent to each other and simultaneously in sliding contact with an outer circumferential surface of the cam.

While the first printing head is movable in the first direction, the second printing head is movable in the second direction. To drive a plurality of printing heads set to move in different directions, generally, head driving mechanisms are provided for the respective printing heads. In addition, a cam mechanism is widely employed for driving the printing heads. According to the present invention, in contrast, a single head driving mechanism drives the plurality of printing heads each set to move in different directions. Such a configuration contributes to reducing the size and the manufacturing cost of the printing apparatus, compared with the configuration in which the head driving mechanisms are provided for the respective printing heads.

Further, in the case of driving the printing head by using the cam, providing the head driving mechanisms for the respective printing heads incurs a positioning error among the printing heads, originating from individual variation among the

cams of the head driving mechanisms, which leads to degradation in printing accuracy. According to the present invention, in contrast, a single cam is utilized in common by the plurality of printing heads. Therefore, the plurality of printing heads can be properly positioned free from the influence of the individual variation among the cams, and a highly accurate printing result can be obtained.

In the foregoing printing apparatus, the first direction and the second direction may be set to radially extend from the rotation axis of the roller. In this case, the first direction becomes perpendicular to the roller surface, at the position where the first liquid dispensed from the first printing head lands on the recording medium. Likewise, the second direction becomes perpendicular to the roller surface, at the position where the second liquid dispensed from the second printing head lands on the recording medium. These printing heads are positioned by a single cam, so that the paper gap, i.e., the distance between the printing head and the recording medium is adjusted. Such a configuration prevents the paper gap from being adjusted to different values among the printing heads, and thereby provides a highly accurate printing result.

In the foregoing head driving mechanism, the first sliding-contact surface and the second sliding-contact surface may be oriented downward in the vertical direction, and in contact with the outer circumferential surface of the cam. In this case, the self-weight of the first cam follower and the components connected thereto assures that the first sliding-contact surface makes contact with the outer circumferential surface of the cam. Likewise, the self-weight of the second cam follower and the components connected thereto assures that the second sliding-contact surface makes contact with the outer circumferential surface of the cam. Such a configuration eliminates the need to provide an additional mechanism to assure that the sliding-contact surfaces make contact with the outer circumferential surface of the cam.

The outer circumferential surface of the cam may include a first adjustment region that varies a distance between the cam shaft and the outer circumferential surface in a first variation pattern, and a second adjustment region that varies the distance between the cam shaft and the outer circumferential surface in a second variation pattern, the second adjustment region continuously extending from the first adjustment region, so that the first printing head and the second printing head are positioned in a vertical direction on the basis of the first variation pattern, while the first sliding-contact surface and the second sliding-contact surface are in sliding contact with the first adjustment region to rotate the cam, and that the first printing head and the second printing head are positioned in a vertical direction on the basis of the second variation pattern, while the first sliding-contact surface and the second sliding-contact surface are in sliding contact with the second adjustment region to rotate the cam. Preparing thus the two types of variation patterns in advance improves the versatility of the head driving mechanism. For example, as will be described in details regarding an embodiment, the plurality of printing heads can be moved in suitable variation patterns for a printing job and a capping operation respectively, and thus the printing job and the capping operation can be optimized.

The head driving mechanism may further include a first engaging portion provided on the other end portion of the first cam follower, a second engaging portion provided on the other end portion of the second cam follower, a first restriction member having an end portion attached to the cam shaft or the cam to rotate with the cam in an interlocked manner and the other end portion to be located above the second adjustment region in the vertical direction so as to hold the first

engaging portion between the second adjustment region and the first restriction member to restrict the first cam follower from moving in the vertical direction, while the second adjustment region of the cam is in sliding contact with the first sliding-contact surface, and a second restriction member having an end portion attached to the cam shaft or the cam to rotate with the cam in an interlocked manner and the other end portion to be located above the second adjustment region in the vertical direction so as to hold the second engaging portion between the second adjustment region and the second restriction member to restrict the second cam follower from moving in the vertical direction, while the second adjustment region of the cam is in sliding contact with the second sliding-contact surface. Such a configuration allows, as will be described regarding an embodiment, the printing heads to move in a desired direction by using the rotation of the cam, even when the printing heads are subjected to a stress in a direction opposite to the moving direction.

BRIEF DESCRIPTION OF THE DRAWINGS

The invention will be described with reference to the accompanying drawings, wherein like numbers reference like elements.

FIG. 1 is a schematic plan view showing a layout of a printing apparatus including a head driving mechanism according to an embodiment of the present invention.

FIG. 2 is a schematic front view of the printing apparatus shown in FIG. 1.

FIG. 3 is a perspective view showing a configuration of the head driving mechanism that moves printing heads to proper positions.

FIG. 4 is an enlarged perspective view showing a part of the head driving mechanism shown in FIG. 3.

FIG. 5 is an exploded perspective view showing a cam and engaging members in the head driving mechanism shown in FIG. 3.

FIGS. 6A to 6D are schematic front views showing operations of the head driving mechanism shown in FIG. 3.

DESCRIPTION OF EXEMPLARY EMBODIMENTS

FIG. 1 is a schematic plan view showing a layout of a printing apparatus including a head driving mechanism according to an embodiment of the present invention. FIG. 2 is a schematic front view of the printing apparatus shown in FIG. 1. The printing apparatus 1 includes a delivery unit 2, processing unit 3, and a take-up unit 4 aligned in a left-right direction on the front side of the apparatus, and a maintenance unit 5 located on the rear side of the processing unit 3, which includes a processor 3U set to move interlocked with the processing unit 3, with respect to the maintenance unit 5. In these drawings, as well as in the drawings to be referred to later, a three-dimensional coordinate system is adapted, in which the axes respectively correspond to the left-right direction X, a front-back direction Y, and a vertical direction Z of the printing apparatus 1.

As shown in FIG. 2, in the printing apparatus 1 the delivery unit 2 and the take-up unit 4 include a delivery shaft 20 and a take-up shaft 40, respectively. The sheet S (web) is spanned between the delivery unit 2 and the take-up unit 4, with end portions respectively wound in a roll around the delivery shaft 20 and the take-up shaft 40. The sheet S is transported from the delivery shaft 20 to the processing unit 3 along the route P_c spanned as above, and then to the take-up shaft 40 after undergoing the printing operation by the processor 3U. The

types of the sheet S, exemplifying the recording medium according to the present invention, may be broadly classified into paper sheets and film sheets. Examples of the paper sheets include wood-free paper, cast-coated paper, art paper, and coated paper. Examples of the film sheets include polyethylene terephthalate (PET) and polypropylene (PP). In the description given below, a surface of the sheet S on which images are recorded will be referred to as front surface, and the surface opposite to the front surface will be referred to as back surface.

The delivery unit 2 includes the delivery shaft 20 on which the end portion of the sheet S is wound, and a slave roller 21 with which the sheet S drawn out from the delivery shaft 20 is engaged. The sheet S is supported by the delivery shaft 20, with the front surface oriented outward. When the delivery shaft 20 rotates clockwise in FIG. 2, the sheet S wound around the delivery shaft 20 is delivered to the processing unit 3 through the slave roller 21. Here, the sheet S is wound on the delivery shaft 20 by means of a core shaft (not shown) removably attached to the delivery shaft 20. Accordingly, when the sheet S on the delivery shaft 20 is used up, the sheet S can be replaced by attaching a new core shaft having the sheet S wound thereon in a roll to the delivery shaft 20. A code Se in FIG. 2 denotes an edge sensor that detects the edges of the sheet S in the width direction, between the slave roller 21 and a front driving roller 31.

The processing unit 3 supports the sheet S delivered from the delivery unit 2 on the platen drum 30, and causes the processor 3U disposed along an outer circumferential surface of the platen drum 30 to perform a predetermined operation for printing images on the sheet S. The processing unit 3 includes the front driving roller 31 and a rear driving roller 32 on the respective sides of the platen drum 30, and the sheet S transported from the front driving roller 31 to the rear driving roller 32 is supported by the platen drum 30 and undergoes the printing process.

The front driving roller 31 includes a plurality of minute projections formed by thermal spraying on the outer circumferential surface, on which the back surface of the sheet S delivered from the delivery unit 2 is engaged. When the front driving roller 31 rotates clockwise in FIG. 2, the sheet S delivered from the delivery unit 2 is transported to the downstream side of the transport route. The front driving roller 31 is provided with a nip roller 31n. The nip roller 31n is biased toward the front driving roller 31 and in contact with the front surface of the sheet S, to pinch the sheet S in collaboration with the front driving roller 31. Such a configuration secures frictional force between the front driving roller 31 and the sheet S, thereby assuring the transport of the sheet S with the front driving roller 31.

The platen drum 30 is a cylindrical drum supported by a supporting mechanism (not shown) so as to rotate about a rotation shaft 301 extending in the Y-direction, and the back surface of the sheet S transported from the front driving roller 31 to the rear driving roller 32 is engaged with the platen drum 30. The platen drum 30 supports the sheet S from the side of the back surface, while being made to rotate by frictional force with sheet S in the transport direction Ds thereof. Here, the processing unit 3 includes slave rollers 33, 34 that serve to fold back the sheet S on the respective sides of the portion thereof engaged with the platen drum 30. The slave roller 33 is engaged with the front surface of the sheet S between the front driving roller 31 and the platen drum 30, to fold back the sheet S. Likewise, the slave roller 34 is engaged with the front surface of the sheet S between the platen drum 30 and the rear driving roller 32, to fold back the sheet S. Folding back the sheet S as above both upstream and downstream of the platen

drum 30 in the transport direction Ds allows a longer engaging portion between the sheet S and the platen drum 30 to be secured.

The rear driving roller 32 includes a plurality of minute projections formed by thermal spraying on the outer circumferential surface, on which the back surface of the sheet S transported from the platen drum 30 through the slave roller 34 is engaged. When the rear driving roller 32 rotates clockwise in FIG. 2, the sheet S is transported toward the take-up unit 4. The rear driving roller 32 is provided with a nip roller 32n. The nip roller 32n is biased toward the rear driving roller 32 and in contact with the front surface of the sheet S, to pinch the sheet S in collaboration with the rear driving roller 32. Such a configuration secures frictional force between the rear driving roller 32 and the sheet S, thereby assuring the transport of the sheet S with the rear driving roller 32.

The sheet S thus transported from the front driving roller 31 to the rear driving roller 32 is supported by the outer circumferential surface of the platen drum 30. The processing unit 3 includes the processor 3U that prints color images on the front surface of the sheet S supported by the platen drum 30. The processor 3U includes a front plate 35a and a rear plate 35b (see FIG. 3) that constitute a pair in the front-back direction. The plates 35a, 35b each have an arcuate shape along the outer circumferential surface of the platen drum 30, and are connected to each other by a joint member (not shown) so as to form a unit frame. To the unit frame, constituents of the processor 3U (printing heads 36a to 36e, UV lamps 37a, 37b, and head driving mechanisms) are attached as will be described later.

Four printing heads 36a to 36d respectively corresponding to yellow, cyan, magenta, and black ink are aligned in this order in the transport direction Ds. In other words, the four printing heads 36a to 36d are radially disposed about the rotation shaft 301 of the platen drum 30. Out of the printing heads 36a to 36d, two upstream printing heads 36a and 36b in the transport direction Ds are moved and positioned with respect to the sheet S wound on the platen drum 30, by a single head driving mechanism. Likewise, the remaining printing heads 36a, 36b on the downstream side are moved and positioned with respect to the sheet S wound on the platen drum 30, by another head driving mechanism. With the two head driving mechanisms that move the four printing heads 36a to 36d to predetermined positions, a distance between the nozzle tip (outlet of the ink) of the printing heads 36a to 36d and the sheet S, i.e., the paper gap, can be adjusted to a proper value. When the printing heads 36a to 36d dispense the ink onto the sheet S wound on the outer circumferential surface of the platen drum 30 with the paper gap adjusted as above, a color image is formed on the front surface of the sheet S. Employing thus one head driving mechanism to move two printing heads to a proper position is one of distinctive features of the present invention, and details of the configuration and operation of the head driving mechanism will be subsequently described.

The liquid such as ink or recording fluid to be used in the printing heads 36a to 36d can be typically exemplified by ultraviolet (UV) ink (photocurable ink) that is cured when irradiated with ultraviolet ray (light). Accordingly, the processor 3U includes UV lamps 37a, 37b (light emitting units) that cures and fixes the ink on the sheet S. The curing of the ink is performed in two stages, namely tentative curing and complete curing. The UV lamps 37a for tentative curing are located between the adjacent ones of the printing heads 36a to 36d. The UV lamps 37a emit relatively weak ultraviolet ray to cure the ink to such an extent that the shape of the ink is prevented from collapsing (tentative curing), and not to com-

pletely cure the ink. The UV lamp **37b** for complete curing is located downstream of the printing heads **36a** to **36d** in the transport direction **Ds**. The UV lamp **37b** emits more intense ultraviolet ray than that from the UV lamps **37a**, to thereby completely cure the ink (complete curing). The color image formed by the printing heads **36a** to **36d** can be fixed to the front surface of the sheet **S**, by performing the tentative curing and the complete curing.

Further, a printing head **36e** is provided downstream of the UV lamp **37b** in the transport direction **Ds**. The printing head **36e** is disposed to oppose the front surface of the sheet **S** wound on the platen drum **30** with a certain gap therebetween, and dispenses transparent UV ink onto the front surface of the sheet **S** by an ink jet method. In other words, the transparent ink is additionally dispensed onto the color image composed of the four colors by the printing heads **36a** to **36d**. Here, the printing head **36e** is independently driven and positioned by another head driving mechanism than the foregoing head driving mechanisms, to set the paper gap at a proper value.

The printing heads **36a** to **36e**, the UV lamps **37a**, **37b** and the head driving mechanisms are attached to the unit frame as above, thus constituting the processor **3U**. The processor **3U** is located between the delivery unit **2** and the take-up unit **4** as indicated by solid lines in FIG. 1, when a normal operation, i.e., the printing operation, is performed. In contrast, the processor **3U** is moved to the maintenance unit **5** by a sliding mechanism (not shown) as indicated by dash-dot lines in FIG. 1, when a maintenance operation for the processor **3U**, for example wiping or capping of the printing heads **36a** to **36e**, is performed.

Referring again to FIG. 2, the configuration of the processing unit **3** and the take-up unit **4** will be described further. In the processing unit **3**, the UV lamp **38** is provided downstream of the printing head **36e** in the transport direction **Ds**. The UV lamp **38** emits intense ultraviolet ray to completely cure the transparent ink dispensed by the printing head **36e**. Accordingly, the transparent ink can be fixed to the front surface of the sheet **S**.

The sheet **S** having the color image formed thereon by the processing unit **3** is transported by the rear driving roller **32** to the take-up unit **4**. The take-up unit **4** includes, in addition to the take-up shaft **40** on which the end portion of the sheet **S** is wound, a slave roller **41** engaged with the back surface of the sheet **S** between the take-up shaft **40** and the rear driving roller **32**. The take-up shaft **40** takes up the end portion of the sheet **S** and supports the sheet **S**, with the front surface oriented outward. To be more detailed, when the take-up shaft **40** rotates clockwise in FIG. 2, the sheet **S** transported from the rear driving roller **32** is taken up by the take-up shaft **40** through the slave roller **41**. Here, the sheet **S** is wound on the take-up shaft **40** by means of a core shaft (not shown) removably attached to the take-up shaft **40**. Accordingly, when the sheet **S** on the take-up shaft **40** becomes full, the sheet **S** can be removed utilizing the core shaft as a support.

Referring now to FIGS. 3 through **6D**, the head driving mechanism provided in the processor **3U**, in particular the head driving mechanism that drives two printing heads will be described in details.

FIG. 3 is a perspective view showing a configuration of two printing heads and the head driving mechanism that moves the printing heads to proper positions. FIG. 4 is an enlarged perspective view showing a part of the head driving mechanism shown in FIG. 3. FIG. 5 is an exploded perspective view showing a cam and engaging members in the head driving mechanism shown in FIG. 3. FIGS. **6A** to **6D** are schematic front views showing operations of the head driving mechanism shown in FIG. 3. These drawings only show the head

driving mechanism **6** that drives the printing heads **36c**, **36d**, and exclude the remaining portions. The configuration and operation of the head driving mechanism **6** will be described referring to the aforementioned drawings, and since another head driving mechanism that drives the printing heads **36a**, **36b** is configured in the same way, the description thereof will not be repeated.

The head driving mechanism **6** moves the printing head **36c** in a first direction **D1** to a proper position, the first direction **D1** being perpendicular to the tangential line of the platen drum **30** at the position where the printing head **36c** performs the printing (landing position of the magenta ink), in other words the radial direction from the rotation shaft **301** of the platen drum **30** that passes the landing position of the magenta ink. At the same time, the head driving mechanism **6** moves the printing head **36d** in a second direction **D2** to a proper position, the second direction **D2** being perpendicular to the tangential line of the platen drum **30** at the position where the printing head **36d** performs the printing (landing position of the black ink), in other words the radial direction from the rotation shaft **301** of the platen drum **30** that passes the landing position of the black ink. In this embodiment, accordingly, the moving directions **D1**, **D2** of the printing heads **36c**, **36d** are inclined from each other by an angle θ (see FIG. **6A**), and the head driving mechanism **6** is configured to move the printing heads **36c**, **36d** to the proper positions maintaining the angular relationship. The head driving mechanism **6** includes a holder **61c** that retains the printing head **36c**. The holder **61c** includes a front holding member **611**, a rear holding member **612**, and a joint plate **613** that connects the holding members **611**, **612**. The printing head **36c** can be removably inserted in the holder **61c** from the (-Y) direction, through an opening **614** formed in the rear holding member **612**.

A linear guide **62** extending in the first direction **D1** is provided on the front face of the front holding member **611** and the rear face of the rear holding member **612**, so as to allow the holder **61c** to move in the first direction **D1** with respect to the front plate **35a** and the rear plate **35b**. To be more detailed, as shown in FIG. 3, a linear rail **621** is fixed to the front face of the front holding member **611** so as to extend in the first direction **D1**, and a pair of sliders **622**, **622** are attached along the rail **621** so as to slide in the first direction **D1**. The sliders **622**, **622** are fixed to the rear face of the front plate **35a**. Likewise, the linear guide **62** of the same shape as that on the front holding member **611** is attached to the rear face of the rear holding member **612**, and the sliders **622**, **622** that can slide along the linear guide **62** are fixed to the front face of the rear plate **35b**. Providing thus the linear guide **62**, **62** on the front and rear sides of the holder **61c** enables the holder **61c** to move in the first direction **D1** with the printing head **36c** retained therein.

The head driving mechanism **6** also includes a holder **61d** that retains the printing head **36d**, located downstream of the holder **61c** in the transport direction **Ds** with a predetermined interval therefrom. The holder **61d** includes, like the holder **61c**, the front holding member **611**, the rear holding member **612**, and the joint plate **613**, and the printing head **36d** can be removably inserted in the holder **61d** through the opening **614** formed in the rear holding member **612**.

In addition, a linear guide **62** extending in the second direction **D2** is provided on the front face of the front holding member **611** and the rear face of the rear holding member **612**, so as to allow the holder **61d** to move in the second direction **D2** with respect to the front plate **35a** and the rear plate **35b**. The configuration of the linear guides **62** provided on the holder **61d** is the same as those on the holder **61c** except that

the rails 621 extend in different directions. Therefore, the same numerals are adopted and detailed description will not be repeated.

A left cam follower 63c, having an end portion (left end portion) fixed to the front holding member 611 of the holder 61c, extends to the right toward the holder 61d, i.e., in the (-X) direction, so that the other end portion (right end portion) of the left cam follower 63c reaches the middle position between the respective front holding members 611 of the holders 61c, 61d. As shown in FIG. 4, the other end portion of the left cam follower 63c has the rear side cut away by half a thickness thereof to be formed into a thinner portion, and an engaging pin 64c projecting to the front side, i.e., in the (+Y) direction is provided on the thinner portion.

Likewise, a right cam follower 63d, having an end portion (right end portion) fixed to the front holding member 611 of the holder 61d, extends to the left toward the holder 61c, i.e., in the (+X) direction, so that the other end portion (left end portion) of the right cam follower 63d reaches the middle position between the respective front holding members 611 of the holders 61c, 61d. As shown in FIG. 4, the other end portion of the right cam follower 63d has the front side cut away by half a thickness thereof to be formed into a thinner portion, and an engaging pin 64d projecting to the rear side, i.e., in the (-Y) direction is provided on the thinner portion. Further, the thinner portions of the left and right cam followers 63c, 63d are disposed in sliding contact with each other at the middle position between the holders 61c, 61d, with the lower face of the other end portion of the left cam follower 63c and the lower face of the other end portion of the right cam follower 63d located adjacent to each other.

At the middle position between the holders 61c, 61d, further, a cam 65 is pivotally located at a predetermined position. The cam 65 is constantly located under the other end portions of the cam followers 63c, 63d, such that the outer circumferential surface of the cam 65 makes contact with the respective lower faces of the thinner portions of the cam followers 63c, 63d so as to support the other end portions of the cam followers 63c, 63d. The cam 65 is slightly thicker than the cam followers 63c, 63d, and attached to a cam shaft 66 extending in the front-back direction Y. The cam shaft 66 is connected to a rotary actuator 68 such as a motor through a power transmission unit 67, so that the rotative driving force generated by the rotary actuator 68 is transmitted to the cam shaft 66 through the power transmission unit 67. With such a configuration, the cam shaft 66 can rotate about its axial center, thereby causing the cam 65 to pivotally rotate.

In this embodiment, the cam followers 63c, 63d are mildly bent at a central portion, such that the respective lower faces of the other end portions of the cam followers 63c, 63d become perpendicular to an imaginary line passing the cam shaft 66 and defining an angle of 0/2 with respect to the first direction D1 and the second direction D2, as shown in FIG. 6A. Such a configuration allows the lower faces of the cam followers 63c, 63d to be stably in contact with the cam 65 irrespective of the pivoting angle thereof, to thereby stably move the printing heads 36c, 36d toward and away from the platen drum 30, as will be subsequently described in further details.

Further, as shown in FIGS. 4 and 5, an engaging member 69c having a hook portion 691 that can be engaged with the engaging pin 64c is attached to the cam 65 and the cam shaft 66 on the front side (on the (+Y) side) of the cam 65, and an engaging member 69d having a hook portion 691 that can be engaged with the engaging pin 64d is attached to the cam 65 and the cam shaft 66 on the rear side (on the (-Y) side) of the cam 65. As will be described below in details, the outer

circumferential surface of the cam 65 includes a printing adjustment region 651 that continuously varies the distance between the cam shaft 66 and the outer circumferential surface of the cam 65 so as to position the printing nozzle at the printing position, and a capping adjustment region 652 that continuously varies the distance between the cam shaft 66 and the outer circumferential surface of the cam 65 so as to position the printing nozzle at the capping position, the capping adjustment region 652 continuously extending from the printing adjustment region 651. In this embodiment, the distance between the cam shaft 66 and the outer circumferential surface of the cam 65 is varied by the printing adjustment region 651 in a pattern suitable for the printing operation, and by the capping adjustment region 652 in a pattern suitable for the capping operation, and the patterns are different from each other. When the capping adjustment region 652 makes contact with the respective lower faces of the other end portions of the cam followers 63c, 63d, the hook portions 691 reach a position above the cam 65 so as to be engaged with the engaging pins 64c, 64d. In other situations, the hook portions 691 are located at a position lower than the engaging pins 64c, 64d.

The operation of the thus-configured head driving mechanism 6 will be described in details referring to FIGS. 6A to 6D. In this embodiment, when neither the printing operation nor the maintenance operation is performed, an end portion of the printing adjustment region 651 of the cam 65 (farthest from the capping adjustment region 652) is located at the highest position in the vertical direction Z and in contact with the respective lower faces of the other end portions of the cam followers 63c, 63d. In this state, the printing heads 36c, 36d are positioned in a home position, at which the nozzle tips of the printing heads 36c, 36d are spaced from the platen drum 30 by a predetermined distance longer than the paper gap.

When the printing operation is to be performed on the sheet S having the respective end portions wound on the delivery unit 2 and the take-up unit 4 and being spanned therebetween, the rotary actuator 68 rotates by an amount corresponding to the thickness of the sheet S in accordance with an operation instruction from a control unit of the overall apparatus, to cause the cam 65 to rotate clockwise in FIG. 6A until the middle position of the printing adjustment region 651 of the cam 65 reaches the highest position in the vertical direction Z. In this embodiment, the cam followers 63c, 63d are located right on top of the cam 65 in the vertical direction Z, and hence pressed against the cam 65 by the self-weight. Accordingly, with the rotation of the cam 65, the cam followers 63c, 63d descend in the vertical direction Z at the same time and by the same distance, while the respective lower faces of the other end portions of the cam followers 63c, 63d make sliding contact with the outer circumferential surface of the cam 65. As a result, the holder 61c connected to the cam follower 63c descends in the first direction D1, so that the printing head 36c retained by the holder 61c is positioned at the printing position determined according to the thickness of the sheet S. Thus, the distance between the nozzle tip of the printing head 36c and the sheet S is adjusted to the desired paper gap.

At the same time as the positioning of the printing head 36c, the positioning of the printing head 36d is also performed. To be more detailed, the holder 61d connected to the cam follower 63d descends in the second direction D2, so that the printing head 36d retained by the holder 61d is positioned at the printing position, and the distance between the nozzle tip of the printing head 36d and the sheet S is adjusted to the desired paper gap. Since the distance between the cam shaft 66 and the outer circumferential surface of the cam 65 is continuously varied by the printing adjustment region 651 in

11

this embodiment, the printing heads **36c**, **36d** can be positioned with high accuracy by controlling the rotational angle of the cam **65**, and thus the desired paper gap can be securely achieved.

The printing heads **36a**, **36b** can also be properly positioned as the printing heads **36c**, **36d**, by the head driving mechanism having the same configuration as that of the head driving mechanism **6**. The remaining printing head **36e** is positioned by still another head driving mechanism.

Upon completing the setting as above the printing operation is performed, during or after which the maintenance of the processor **3U** has to be performed, according to the operation status of the apparatus. In the maintenance operation, the processor **3U** is moved backward, i.e., in the (-Y) direction as a whole, and undergoes various maintenance works in the maintenance unit **5**. The maintenance works include the capping operation for the printing heads **36a** to **36e**. The capping operation serves to prevent clogging of the nozzles of the printing heads **36a** to **36e**, and the maintenance unit **5** includes a capping mechanism **51** that performs the capping operation as shown in FIGS. **6C** and **6D**. The capping operation is performed as described below, for the processor **3U** moved to the maintenance unit **5**.

The capping mechanism **51** includes cap portions **52** respectively located at fixed positions so as to correspond to the printing heads **36a** to **36e**. When the processor **3U** is moved to the capping mechanism **51**, the printing heads **36a** to **36e** are located above the corresponding cap portions **52** in the vertical direction **Z**. Although only the printing heads **36c**, **36d** are shown in FIGS. **6C** and **6D** as for the printing operation, the remaining printing heads also operate basically in the same way.

When the printing heads **36c**, **36d** are set to correspond to the cap portions **52**, **52**, the rotary actuator **68** rotates in accordance with an operation instruction from the control unit, to cause the cam **65** to rotate clockwise in FIG. **6C** until the boundary between the printing adjustment region **651** and the capping adjustment region **652** of the cam **65** reaches the highest position in the vertical direction **Z**. With the rotation of the cam **65**, the cam followers **63c**, **63d** descend in the vertical direction **Z** at the same time and by the same distance, and the holders **61c**, **61d** connected to the cam followers **63c**, **63d** respectively descend in the first direction **D1** and the second direction **D2**. As a result, the printing heads **36c**, **36d** are set at the position where the respective nozzle tips make contact with the corresponding cap portions **52**.

In addition, with the rotation of the cam **65** the engaging members **69c**, **69d** attached to the cam **65** and the cam shaft **66** also rotate clockwise in FIG. **6C**. Then the hook portion **691** of the engaging member **69c** starts to be engaged with the engaging pin **64c** projecting from the cam follower **63c**. Likewise, although not illustrated in FIG. **6C**, the hook portion **691** of the engaging member **69d** starts to be engaged with the engaging pin **64d** projecting from the cam follower **63d**. In this embodiment, the distance between the capping adjustment region **652** of the cam **65** and the hook portion **691** is generally constant over the entirety of the capping adjustment region **652**, and is slightly larger than the diameter of the engaging pins **64c**, **64d**. Accordingly, the engaging pins **64c**, **64d** are located between the outer circumferential surface of the cam **65** and the hook portion **691** with a certain play.

Thereafter, the rotary actuator **68** further rotates according to an operation instruction from the control unit, to cause the cam **65** to rotate clockwise in FIG. **6C** until the middle position of the capping adjustment region **652** of the cam **65** reaches the highest position in the vertical direction **Z**. During such rotation also, the engaging pins **64c**, **64d** are located

12

between the outer circumferential surface of the cam **65** and the hook portion **691**, and the cam followers **63c**, **63d** descend in the vertical direction **Z** at the same time and by the same distance resisting the pressure applied by the cap portions **52**, so that the holders **61c**, **61d** connected to the cam followers **63c**, **63d** respectively move in the first direction **D1** and the second direction **D2**. As a result, the printing heads **36c**, **36d** are respectively pressed against the cap portions **52**, **52** and the capping operation is performed.

Upon completing the capping operation, the rotary actuator **68** rotates in the reverse direction according to an operation instruction from the control unit, causing the printing heads **36c**, **36d** to ascend. Then the processor **3U** is returned to the processing unit **3**, after undergoing various maintenance works in the maintenance unit **5**.

In this embodiment, as described above, the printing heads **36a** to **36e** are radially located about the rotation shaft **301** of the platen drum **30**. In other words, the dispensing direction of the ink is perpendicular to the surface platen drum **30**, at the respective positions where the ink dispensed from the printing heads **36a** to **36e** lands on the sheet **S** wound on the platen drum **30**. Out of these printing heads, the printing heads **36c**, **36d** are positioned by the single cam **65**, and the distance between the printing head and the recording medium, i.e., the paper gap, is adjusted. Such a configuration prevents the paper gap from being adjusted to different values between the printing heads **36c**, **36d**. Further, the printing heads **36a**, **36b** are configured in the same way as the printing heads **36c**, **36d**. Consequently, a highly accurate printing result can be obtained.

In addition, the two printing heads **36c**, **36d** set to move in different directions are driven by the single head driving mechanism **6**. This is also the case with the printing heads **36a**, **36b**. Such a configuration contributes to reducing the size and the manufacturing cost of the printing apparatus, compared with the configuration in which the head driving mechanisms are provided for the respective printing heads.

Further, the single cam **65** drives the both printing heads **36c**, **36d**, in other words the cam **65** is utilized in common by the printing heads **36c**, **36d**. Therefore, the printing heads **36c**, **36d** can be properly positioned free from the influence of the individual variation between the cams. In this aspect also, the printing heads **36a**, **36b** are configured in the same way as the printing heads **36c**, **36d**. Consequently, a highly accurate printing result can be obtained.

Further, the outer circumferential surface of the cam **65** includes two adjustment regions, namely the printing adjustment region **651** and the capping adjustment region **652**, so as to move the printing heads **36a** to **36d** in the patterns suitable for the printing operation and the tapping operation.

Still further, in the foregoing embodiment the cam followers **63c**, **63d** respectively include the engaging pins **64c**, **64d**, and also the engaging members **69c**, **69d** that can be respectively engaged with the engaging pins **64c**, **64d** are provided, so that the engaging members **69c**, **69d** are engaged with the engaging pins **64c**, **64d** in the capping operation. Such a configuration enables the printing heads **36c**, **36d** to be pressed against the cap portions **52**, **52**, thus assuring that the capping operation is properly performed.

In the foregoing embodiment, the platen drum **30** corresponds to the "roller" according to the present invention. The printing heads **36c**, **36d** respectively correspond to the "first printing head" and the "second printing head" and the holders **61c**, **61d** respectively correspond to the "first holding unit" and the "second holding unit" according to the present invention. The cam follower **63c** corresponds to the "first cam follower" according to the present invention, and the lower

13

face of the other end portion of the cam follower 63c corresponds to the "first sliding-contact surface" according to the present invention. Likewise, the cam follower 63d corresponds to the "second cam follower" according to the present invention, and the lower face of the other end portion of the cam follower 63d corresponds to the "second sliding-contact surface" according to the present invention. In the outer circumferential surface of the cam 65, the printing adjustment region 651 corresponds to the "first adjustment region" and the capping adjustment region 652 corresponds to the "second adjustment region" according to the present invention. Further, the engaging members 69c, 69d respectively correspond to the "first restriction member" and the "second restriction member" according to the present invention.

It is to be noted that the present invention is in no way limited to the foregoing embodiment, but may be modified in various manners within the scope of the present invention. For example, although the head driving mechanism 6 is configured to drive two printing heads at a time in the embodiment, the head driving mechanism 6 may be configured to drive three or more printing heads at a time.

Although the rotative driving force generated by the rotary actuator 68 is applied to the cam shaft 66 through the power transmission unit 67 in the embodiment, the rotary actuator 68 may directly apply the driving force to the cam shaft 66.

Further, although the engaging pins 64c, 64d are respectively attached to the cam followers 63c, 63d for the hook portions 691 to be engaged therewith in the embodiment, a part of the cam followers 63c, 63d may be formed in a projecting shape, and such projections may be employed as the first engaging portion and the second engaging portion according to the present invention. Although the engaging members 69c, 69d are attached to the cam 65 and the cam shaft 66 in the embodiment, the engaging members may be attached only one of the cam 65 and the cam shaft 66, provided that the engaging members can be made to rotate together with the cam 65, by the rotation of the cam shaft 66.

Still further, although the present invention is applied to the head driving mechanism that drives a plurality of printing heads that dispense UV ink in the foregoing embodiment, the present invention is applicable to various different head driving mechanisms.

What is claimed is:

1. A head moving mechanism comprising:
  - a first holding unit that holds a first printing head so as to move together with the first printing head in a first direction;
  - a second holding unit that holds a second printing head so as to move together with the second printing head in a second direction inclined with respect to the first direction;
  - a rotary actuator that generates rotative driving force for moving the first printing head and the second printing head;
  - a cam shaft to be driven to rotate by the rotative driving force from the rotary actuator;
  - a cam attached to the cam shaft;
  - a first cam follower a first end portion of which is attached to the first holding unit and a second end portion of which includes a first sliding-contact surface disposed in sliding contact with the cam; and
  - a second cam follower a third end portion of which is attached to the second holding unit and a fourth end portion of which includes a second sliding-contact surface disposed in sliding contact with the cam,
2. The head moving mechanism according to claim 1, the first cam follower and the second cam follower being each displaced by rotation of the cam so as to move the

14

first holding unit together with the first printing head and move the second holding unit together with the second printing head, while the first sliding-contact surface and the second sliding-contact surface are in sliding contact with an outer circumferential surface of the cam.

2. The head moving mechanism according to claim 1, wherein the first sliding-contact surface and the second sliding-contact surface are oriented downward in a vertical direction, and disposed in contact with an outer circumferential surface of the cam.
3. The head moving mechanism according to claim 2, wherein the outer circumferential surface of the cam includes:
  - a first adjustment region that varies a distance between the cam shaft and the outer circumferential surface in a first variation pattern; and
  - a second adjustment region that varies the distance between the cam shaft and the outer circumferential surface in a second variation pattern, the second adjustment region continuously extending from the first adjustment region,
  - the first printing head and the second printing head are positioned in a vertical direction on the basis of the first variation pattern, while the first sliding-contact surface and the second sliding-contact surface are in sliding contact with the first adjustment region to rotate the cam, and
  - the first printing head and the second printing head are positioned in a vertical direction on the basis of the second variation pattern, while the first sliding-contact surface and the second sliding-contact surface are in sliding contact with the second adjustment region to rotate the cam.
4. The head moving mechanism according to claim 3, further comprising:
  - a first engaging portion provided on the other end portion of the first cam follower;
  - a second engaging portion provided on the other end portion of the second cam follower;
  - a first restriction member having an end portion attached to the cam shaft or the cam to rotate with the cam in an interlocked manner and the other end portion to be located above the second adjustment region in the vertical direction so as to hold the first engaging portion between the second adjustment region and the first restriction member to restrict the first cam follower from moving in the vertical direction, while the second adjustment region of the cam is in sliding contact with the first sliding-contact surface; and
  - a second restriction member having an end portion attached to the cam shaft or the cam to rotate with the cam in an interlocked manner and the other end portion to be located above the second adjustment region in the vertical direction so as to hold the second engaging portion between the second adjustment region and the second restriction member to restrict the second cam follower from moving in the vertical direction, while the second adjustment region of the cam is in sliding contact with the second sliding-contact surface.
5. The head moving mechanism according to claim 1, wherein
  - the first cam follower extends in a third direction intersecting the first direction and a shaft direction of the cam shaft, the first end portion and the second end portion are opposite each other in the third direction,
  - the second cam follower extends in a fourth direction intersecting the second direction and the shaft direction, the

15

third end portion and the fourth end portion are opposite each other in the fourth direction, and the second portion of the first cam follower and the fourth end portion of the second cam follower slidably contact each other.

6. The head moving mechanism according to claim 5, wherein

the first end portion has a first width in the shaft direction, the second end portion has a second width in the shaft direction, which is smaller than the first width.

7. The head moving mechanism according to claim 5, wherein

the third end portion has a third width in the shaft direction, the fourth end portion has a fourth width in the shaft direction, which is smaller than the third width.

8. The head moving mechanism according to claim 5, wherein

the second end portion has a second width in the shaft direction, the fourth end portion has a fourth width in the shaft direction, and the cam shaft has a fifth width in the shaft direction, which is larger than a total width of the second width and the fourth width.

9. A printing apparatus comprising:

a rotatable roller;
a first printing head that dispenses a first liquid in a first direction onto a recording medium wound around a surface of the roller;

a second printing head that dispenses a second liquid in a second direction inclined with respect to the first direction onto the recording medium wound around the surface of the roller; and

a head moving mechanism that drives the first printing head and the second printing head,

5

10

15

20

25

30

16

the head moving mechanism including
a first holding unit that holds the first printing head so as to move together with the first printing head in the first direction;

a second holding unit that holds the second printing head so as to move together with the second printing head in the second direction;

a rotary actuator that generates rotative driving force for moving the first printing head and the second printing head;

a cam shaft to be driven to rotate by the rotative driving force from the rotary actuator;

a cam attached to the cam shaft;

a first cam follower an end portion of which is attached to the first holding unit and the other end portion of which includes a first sliding-contact surface disposed in sliding contact with the cam; and

a second cam follower an end portion of which is attached to the second holding unit and the other end portion of which includes a second sliding-contact surface disposed in sliding contact with the cam,

the first cam follower and the second cam follower being each displaced by rotation of the cam so as to move the first holding unit together with the first printing head and move the second holding unit together with the second printing head, while the first sliding-contact surface and the second sliding-contact surface are located adjacent to each other and simultaneously in sliding contact with an outer circumferential surface of the cam.

10. The printing apparatus according to claim 9, wherein the first direction and the second direction radially extend from the rotation axis of the roller.
